DESIGN FOR AN ELECTRIC RANGE, OR SIMILAR ARTICLE

Richard B. Marshall, Detroit, Mich., assignor to Electromaster, Inc., Detroit, Mich., a corporation of Michigan

Application June 24, 1944, Serial No. 114,176

Term of patent 14 years

(Cl. D81—4)

To all whom it may concern:

Be it known that I, Richard B. Marshall, a citizen of the United States and a resident of the city of Detroit, in the county of Wayne and State of Michigan, have invented a new, original, and ornamental Design for an Electric Range, or Similar Article, of which the following is a specification, reference being had to the accompanying drawing, forming a part thereof.

On the drawing:

The figure illustrates a perspective view of the electric range, or similar article, showing my new design.

The side not shown is substantially the same as the side shown.

I claim:

The ornamental design for an electric range or similar article, as shown and described.

RICHARD B. MARSHALL.
